United States Patent Office

Des. 207,072
Patented Feb. 28, 1967

207,072

REPRODUCTION MACHINE

John R. Regal, East Brunswick, N.J., assignor to Sperry
Rand Corporation, New York, N.Y., a corporation of
Delaware

Filed Oct. 18, 1965, Ser. No. 87,579

Term of patent 14 years

(Cl. D61—1)

FIG. 1.

FIG. 2.

FIG. 3.

FIG. 4.

FIG. 1 is a front perspective view of a reproduction machine showing my new design;

FIG. 2 is a rear perspective view thereof;

FIG. 3 is a side elevational view thereof; and

FIG. 4 is a top view thereof.

The essential features of my design are shown in full lines.

I claim:

The ornamental design for a reproduction machine, substantially as shown and described.
